UNITED STATES PATENT OFFICE

2,505,914

CLOTHES HANGER WITH ADJUSTABLE
SHOULDER PIECES

Louis Ronzio, St. Louis, Mo.

Application June 3, 1947, Serial No. 752,131

1 Claim. (Cl. 223—89)

1

This invention relates to new and useful improvements and structural refinements in clothes hangers, more specifically, adjustable coat and pants hangers, and the principal object of the invention is to provide a device of the character herein described, which embodies in its construction adjustable shoulder pieces slidably mounted on the limbs of the hanger, whereby the overall length or span of the hanger may be easily and conveniently adjusted to suit the "shoulder width" of the coat or jacket hung upon the same.

A further object of the invention is to provide a clothes hanger which, by virtue of the construction above outlined, will effectively assist in maintaining the clothes in better shape and form, and will eliminate the conventionally experienced formation of creases or wrinkles resulting from the use of a hanger which is too "small" for the coat or jacket positioned thereon.

Another object of the invention is to provide an adjustable clothes hanger which is simple in construction and in which the adjustment of the "span" may be quickly and easily effected.

An additional object of the invention is to provide an adjustable clothes hanger which will readily lend itself to economical manufacture and which is otherwise well adapted for the purpose for which it is intended.

With the above more important objects in view and such other objects as may become apparent as this specification proceeds, the invention consists essentially of the construction and arrangement of parts as shown in the accompanying drawings in which:

Figure 1 is an elevational view of the invention;

Figure 2 is a fragmentary plan view, taken substantially in the plane of the line 2—2 in Figure 1;

Figure 3 is a fragmentary perspective view showing a portion of the supporting member used in the hanger and the manner in which it is attached to the suspension hook;

Figure 4 is a cross sectional view, taken substantially in the plane of the line 4—4 in Figure 1;

Figure 5 is a cross sectional view, taken substantially in the plane of the line 5—5 in Figure 1; and

Figure 6 is a cross sectional view, taken substantially in the plane of the line 6—6 in Figure 1.

Like characters of reference are used to designate like parts in the specification and throughout the several views.

Referring now to the accompanying drawings in detail, the invention consists of an adjustable clothes hanger designated generally by the reference character 10, the same embodying in its con-

struction the supporting member 11 which includes a pair of downwardly and outwardly extending strap-like limbs 12 and 13.

The outer ends of these limbs are connected together by means of a cross-bar 14, the latter, in effect, being formed integrally with the limbs 12, 13 from one piece of material, the intermediate portion of which constitutes the cross-bar, while its end portions are angulated to provide the limbs 12, 13, as will be clearly apparent. The adjacent inner end portions of the limbs 12, 13 are secured together by welding, or the like, as indicated at 15, and it will be noted that while the limbs, in view of their strap-like configuration, are disposed on edge, as it were, the material forming the cross-bar 14 is horizontally "flat," so to speak, this being accomplished by the formation of suitable twists 16, as is best shown in Figures 1 and 4.

It will be also noted that the cross-bar 14 is upwardly convexed as at 17, so that trousers, or the like, may be positioned thereon without creasing.

The juxtaposed end portions of the limbs 12, 13 which are secured together are formed with outward arcuations defining an opening 18 in order to accommodate a suitable bushing 19. This bushing, in turn, accommodates the shank portion 20 of a rotatable suspension hook 21, the latter extending upwardly and providing means whereby the entire hanger may be suspended from suitable supporting structure (not shown).

Needless to say, the lower end of the hook portion 20 may be flared so as to provide a retaining shoulder 22, whereby separation of the hook from the hanger is prevented.

The essence of the invention resides in the provision of a pair of shoulder-pieces 23, each of which is slidably mounted on the outer end portion of one of the limbs 12, 13. Each of these shoulder-pieces consists of a strip of resilient material which is doubled upon itself, as it were, to provide a pair of arms 24 which receive therebetween the end portions of the associated limb of the hanger.

It will be observed that the closed end portion of the shoulder-pieces 23 is relatively wide as indicated at 25, so as to provide substantial support for the shoulder of the coat or jacket positioned on the hanger. The free end portions of the shoulder-pieces are angulated to provide inturned detents 26, while the intermediate portions of the arms 24 are inwardly arcuated so that they frictionally engage the associated limb of the hanger. It will be apparent that in this manner, the inter-

mediate portions of the arms 24 will provide the necessary frictional contact whereby the shoulder-pieces 23 are retained in slidable engagement with the hanger limbs.

Means are also furnished for retaining the shoulder-pieces on the limbs and, at the same time, for releasably locking the shoulder-pieces in a predetermined position with respect to the limbs, whereby the hanger may be easily and conveniently adjusted to suit coats and jackets of various sizes.

Said means consists of a plurality of locking bands or loops 27, each of which is formed from a strip of suitable material and assumes the configuration best illustrated in the accompanying Figure 5.

These bands are positioned, preferably in pairs, on the shoulder-pieces 23 so that they encircle the arms 24, matters being so arranged that when the bands 27 on each of the shoulder-pieces are drawn together, (see 28 in Figure 2), they will be disposed on the concaved or inwardly arcuated midportion of the arms and, as a result, the frictional engagement of the arms on the associated limbs will be relaxed and the shoulder-pieces may be slid inwardly and outwardly, as desired, and indicated by the arrows 29.

It will be apparent that in this manner, the hanger may be adjusted so as to suit different shoulder "spans" of various coats and jackets such as may be positioned thereon.

When it is desired to lock the shoulder-pieces in a predetermined relative position with respect to the limbs of the hanger, it is only necessary to slide apart the bands 27 on each shoulder piece, whereby the arms 24, particularly the end portions 26 thereof, will be urged into firm frictional engagement with the associated limbs, so that further sliding of the shoulder pieces with respect to the limbs will be prevented.

It is believed that the advantages and use of the invention will be clearly apparent from the foregoing disclosure and accordingly, further description thereof at this point is deemed unnecessary.

While in the foregoing there has been shown and described the preferred embodiment of this invention it is to be understood that minor changes in the details of construction, combination and arrangement of parts may be resorted to without departing from the spirit and scope of the invention as claimed.

Having described the invention, what is claimed as new is:

15 In an adjustable clothes hanger, the combination of a supporting limb having flat opposite side surfaces, a shoulder piece comprising a resilient U-shaped strap affording a relatively wide bight portion and a pair of closely spaced arms terminating at their free ends in turned opposing detents in abutment with the respective side surfaces of said limb, intermediate portions of said arms being bowed toward each other and frictionally engageable with said respective side surfaces, and a keeper loop slidable on said arms toward and away from said detents for respectively locking and unlocking said shoulder piece against sliding movement on said limb.

LOUIS RONZIO.
